Primary Examiner — Eric Goodman*Assistant Examiner* — Christian P McLean(74) *Attorney, Agent, or Firm* — Banner & Witcoff, Ltd.(57) **CLAIM**

The ornamental design for a display screen with animated graphical user interface, as shown and described.

DESCRIPTION

FIG. 1 is the first image in a sequence for a display screen with animated graphical user interface showing the new design;

FIG. 2 is the second image thereof;

FIG. 3 is the third image thereof;

FIG. 4 is the fourth image thereof;

FIG. 5 is the fifth image thereof;

FIG. 6 is the first image in a sequence for a display screen of FIG. 1 shown on a device;

FIG. 7 is the second image thereof;

FIG. 8 is the third image thereof;

FIG. 9 is the fourth image thereof;

FIG. 10 is the fifth image thereof;

FIG. 11 is a rear view of the device thereof;

FIG. 12 is a left side view of the device thereof;

FIG. 13 is a right side view of the device thereof;

FIG. 14 is a top view of the device thereof; and,

FIG. 15 is a bottom view of the device thereof.

The appearance of the animated graphical user interface sequentially transitions between the images shown in FIGS. 1-5 and FIGS. 6-10. The process or period in which one image transitions to another forms no part of the claimed design. The broken line showing of the remainder of the user interface, the remainder of the display screen, and the device is for environmental purposes only and forms no part of the claimed design.
